UNITED STATES PATENT OFFICE.

FREDERICK PURDY, OF KENOSHA, WISCONSIN, ASSIGNOR TO THOMAS B. JEFFERY, OF KENOSHA, WISCONSIN; KATE E. JEFFERY, CHARLES T. JEFFERY, AND HAROLD W. JEFFERY EXECUTORS OF SAID THOMAS B. JEFFERY, DECEASED.

MEANS FOR FACILITATING THE STARTING OF INTERNAL-COMBUSTION ENGINES.

961,077.

Specification of Letters Patent. Patented June 7, 1910.

Application filed December 23, 1908. Serial No. 468,888.

To all whom it may concern:

Be it known that I, FREDERICK PURDY, a citizen of the United States, residing at Kenosha, county of Kenosha, State of Wisconsin, have invented a certain new and useful Improvement in Means for Facilitating the Starting of Internal-Combustion Engines, and declare the following to be a full, clear, and exact description of the same, such as will enable others skilled in the art to which it pertains to make and use the same, reference being had to the accompanying drawings, which form a part of this specification.

One of the disagreeable features of internal combustion engines is the necessity for turning the crank shaft manually, that is, "cranking," in order to start them. Multi-cylinder engines are sometimes enabled to start under their own power upon the completion of the firing circuit. Even in the best forms of multi-cylinder engines this "starting on spark", as it is called, is by no means certain, it being at times absolutely impossible to start them in this manner so that resort must very often be had to the process of cranking. It has generally been believed that the main factors in giving an engine capacity to "start on spark" are the perfection of compression and the absence of unnecessary friction; but engines in which these two conditions are as nearly perfect as it is possible to have them do not always "start on spark" and, in fact, some of them never do.

When an engine is stopped in the usual way the firing circuit is, of course, interrupted before an explosion can take place in the cylinder wherein the piston is just ready to begin or has begun its power stroke. In the ordinary four-cylinder engine, when one piston is on the power stroke, another is on the compression stroke, a third is on the exhaust stroke and the remaining piston is on the intake stroke. Consequently when such an engine stops with the charge behind the piston which is on its working stroke unexploded there will be two cylinders containing charges under compression and two cylinders in which there is no appreciable pressure. If then, there is no loss of compression, the engine should finally come to rest with all of the pistons midway of their strokes, since this is the position of equi-

librium between the two pistons which are under pressure. This position of the pistons is also the most effective one since the leverage between the piston on the working stroke and the crank shaft is at a maximum.

I have found whenever an engine has been able to start under its own power the condition of equilibrium in which the engine was placed was such that the pistons were approximately midway between the ends of their strokes; and where an engine was unable to start under its own power or could only start with difficulty, the piston on its working stroke had come to rest nearer the beginning of the working stroke than the end thereof. This latter condition can, of course, only arise because of a loss of compression in the cylinder wherein the piston is on the working stroke without a corresponding loss of pressure in the cylinder wherein the piston is on the compression stroke. Now in most engines of this class it has been found that the most satisfactory results are produced by opening the exhaust valves before the ends of the working strokes are reached, the cranks connected to the pistons on their working strokes being usually in positions ranging from 30 degrees to 50 degrees away from the position which they occupy when the pistons are at the ends of their working strokes. When, therefore, the engine is stopped, the two opposing elastic cushions working against the pistons which are respectively on their working and compression strokes tend to bring the engine to a condition of rest with the pistons in midway positions: However, there will be more or less oscillation from one side to the other of this natural position of equilibrium and, if the engine is free from friction and the compression space is comparatively large or the fly wheel is quite heavy the oscillation may be so great as to open the exhaust valve associated with the cylinder wherein the piston is on its working stroke, thereby allowing some of the charge to escape and reducing the pressure. As a result the condition of equilibrium will be found not when the pistons are midway of their strokes but when the piston which is on its working stroke has returned more or less toward the beginning of its working stroke. It will be seen that if the reduction of pressure in the power cylinder is considerable the volume

of gas remaining in the power cylinder will not produce sufficient pressure to overcome the angular disadvantage and the increased resistance in the compression cylinder so that, although the charge in the power cylinder may be ignited, it will not start the cycle of operation.

The object of my invention is to prevent the dissipation of the pressure in the power cylinder of a multi-cylinder engine when the engine is stopped so as to permit the engine to start under its own power when the charge in the power cylinder is subsequently ignited.

15 The various features of novelty whereby my invention is characterized will herein-after be pointed out with particularity in the claims; but for a full understanding of my invention and of its object and advantages reference may be had to the following detailed description, taken in connection with the accompanying drawings, wherein:

20 Figure 1 is a front elevation of a multi-cylinder internal combustion engine showing one embodiment of my invention incorporated therein; and Fig. 2 is a section taken through one of the cylinders.

25 It is, of course, evident that various mechanisms or mechanical expedients may be adopted for conserving pressure in the power cylinder when a multi-cylinder internal combustion engine comes to rest and I desire not to be limited to any particular mechanical construction or expedient. In 30 the drawings I have shown one of the simplest arrangements for effecting the desired result.

35 Referring to the drawings, A represents a four-cylinder internal combustion engine, the cylinders being indicated at B—C—D and E respectively.

40 F is an exhaust conduit common to all of the cylinders; b—c—d and e are spark plugs for igniting charges; G is a portion of the energizing circuit for the igniters.

45 By referring to Fig. 2 it will be seen that when the piston H is approaching the end of the power stroke and the crank I connected therewith is still a considerable distance from its lower center, the exhaust valve K is just being opened through the cam L. Assuming that the engine has been stopped by interrupting the igniting circuit before the charge above the piston H has 50 been exploded: If the piston oscillates within sufficiently wide limits to reach the position indicated, the valve K will be opened. The relation of the inlet valve and its actuating cam on the compression cylinder is, of course, such that this valve will 55 not be affected by the oscillation of the engine when seeking its position of equilibrium. Consequently some of the pressure in the power cylinder would ordinarily be dissipated while that in the compression cylinder

60 remained undiminished. When the engine finally came to rest the piston H would not be at the middle of its stroke but would be up near the top of the cylinder, the distance from the center, of course, depending 65 upon the extent to which the pressure on the power cylinder has been impaired. If only a little of the pressure in the power cylinder was lost the position of equilibrium would be such that the engine would still start under its own power. A considerable loss of 70 pressure would, however, make it impossible to start the engine without cranking. The loss of pressure in the power cylinder to a point where the engine will not start under 75 its own power may be avoided by the simple expedient of placing in the exhaust conduit a valve M which is closed when the engine is stopped. If, thereafter, during the oscillation of the engine, the exhaust valve on the power cylinder is opened, the charge in the power cylinder will enter the exhaust conduit until an equalization between the pressure in the conduit and that in the cylinder is effected. As soon as the engine ceases 80 oscillating the exhaust valve will, of course, be closed and if the engine is properly designed the pressure in the power cylinder is 85 maintained for a comparatively long time. When it is desired to 90 start the engine it is only necessary to open the valve M so as to permit the engine to exhaust in a normal manner when it begins to operate. This auxiliary valve may take any desired form, the one which I have 95 found to work quite satisfactorily being in the form of a disk pivoted as at m within the exhaust conduit and arranged so as to make an acute angle with the axis of the conduit when closed. Such a valve may 100 readily be ground to make a tight closure for the conduit. The valve may be operated in any suitable manner as, for example, by means of a lever N and rod O.

105 In order that the breaking of the firing circuit with the closing of the valve may be insured there may be a switch in the firing circuit controlled by the valve so that whenever the valve is closed the firing circuit will be interrupted. In the drawings I have 110 shown such a switch consisting of two stationary contact pieces P and P¹ and a bridge contact P² carried by the operating lever for the valve. When the valve is fully open, as indicated in dotted lines in Fig. 1, the contact piece P² bridges the gap between the two stationary contact pieces and completes the circuit at this point. As soon as the valve is 115 partially closed, however, the movable contact piece is carried out of engagement with the stationary pieces and the circuit is interrupted.

120 While I have described in detail only a single practical form of my invention I desire to cover all other embodiments thereof 125

as will be evident from the terms employed in the definitions of my invention constituting the appended claims.

Having now described my invention, what I claim as new and desire to obtain by Letters Patent is:

1. In an internal combustion engine, a plurality of engine cylinders, pistons in said cylinders, means for normally exhausting pressure from said cylinders at predetermined points between the ends of the working strokes of said pistons, and means for maintaining the cylinders closed against atmosphere when the pistons reach said predetermined points upon stopping the engine so as to maintain pressure in the cylinders.
2. In an internal combustion engine, a plurality of engine cylinders, pistons in said cylinders, means for normally exhausting pressure from said cylinders at predetermined points between the ends of the working stroke of said piston and manually controlled means for preventing the exhausting of pressure at said predetermined points upon stopping the engine.
3. In an internal combustion engine, a plurality of cylinders, pistons in said cylinders, exhaust conduits leading from said cylinders, exhaust valves in said conduits, means for opening said exhaust valves at predetermined points during the working strokes of said pistons and valve mechanism in addition to the exhaust valves for closing said conduits upon stopping the engine.
4. In an internal combustion engine, a plurality of engine cylinders, pistons in said cyl-

inders, an exhaust pipe connected to the exhaust ports of said cylinders, exhaust valves, means for opening said exhaust valves at predetermined points during the working strokes of said pistons, and a tightly seating valve in said pipe adapted to be closed upon stopping the engine.

5. In an internal combustion engine, a plurality of engine cylinders, pistons in said cylinders, a firing circuit, means for normally exhausting pressure from said cylinders at predetermined points between the ends of the working strokes of said pistons, and means for preventing the exhausting of pressure at said predetermined points and at the same time rendering said firing circuit inoperative.

6. In an internal combustion engine, a plurality of cylinders, pistons in said cylinders, exhaust conduits from said cylinders, exhaust valves in said conduits, means for actuating said valves to exhaust pressure from said cylinders at predetermined points between the ends of the working strokes of said pistons, valve mechanism for closing said conduits, a firing circuit, and means associated with said valve mechanism for rendering said circuit inoperative when the valve mechanism is in conduit-closing position.

In testimony whereof, I sign this specification in the presence of two witnesses.

FREDERICK PURDY.
